H. R. CHURCHILL.

WATER HEATER.

APPLICATION FILED JULY 17, 1908.

941,618.

Patented Nov. 30, 1909.

UNITED STATES PATENT OFFICE.

HENRY R. CHURCHILL, OF BUFFALO, NEW YORK.

WATER-HEATER.

941,618.

Specification of Letters Patent. Patented Nov. 30, 1909.

Application filed July 17, 1908. Serial No. 443,957.

To all whom it may concern:

Be it known that I, HENRY R. CHURCHILL, a citizen of the United States, residing at Buffalo, in the county of Erie and State of New York, have invented a certain new and useful Improvement in Water-Heaters, of which the following is a specification.

This invention relates to an improved water heater and the object is to produce a comparatively cheap and economical device with which water may be rapidly heated.

The invention also relates to certain details of construction, which will be herein-after described and claimed reference being had to the accompanying drawings in which,—

Figure 1 is a central vertical section through my improved water heater and a storage tank of ordinary kind to which it is attached, the heat deflectors within the fire tube of the heater being shown in elevation. Fig. 2 is an enlarged plan view of my improved water heater with the upper ring or stove pipe support removed. Fig. 3 is an enlarged transverse section through my improved water heater on line *a a*, Fig. 1. Fig. 4 is an enlarged detached plan view of the burner of my improved water heater. Fig. 5 is an enlarged detached plan view of the upper ring or stove pipe support. Fig. 6 is an enlarged detached side view of one of the cross like heat deflectors. Fig. 7 is a section on line *b b*, Fig. 6. Fig. 8 is a central vertical section through one of the tubular heat deflectors on line *c c*, Fig. 9. Fig. 9 is a transverse section on line *d d*, Fig. 8. Fig. 10 is an enlarged fragmentary central section through the burner. Fig. 11 is an enlarged fragmentary central section through the nozzle of the burner.

In referring to the water heater in detail like numerals designate like parts.

In the accompanying drawings a heater of the improved construction is shown connected to a water tank 1, of conventional type which is mounted on a base 2. A pipe 3 which is connected to a source of water supply serves as the cold water inlet pipe to the water tank. The hot water outlet pipe 4 is connected to the top of the tank and extends to any desired location.

The heating device has two vertical tubes 5 and 6 which are arranged concentrically with each other. These tubes differ in diameter and the smaller tube 5 is located within the larger tube 6 and is sufficiently

smaller than the larger tube to leave an annular space 7 between the tubes. The tubes are joined at their upper and lower ends to entirely close the upper and lower ends of the annular space 7 by rings 8 and 9. These rings are fitted in place between the tubes and are secured to the tube surface by welding or other suitable means, preferably by the autogenous or gas welding method. Pipe connections 10, 11 and 12 are also preferably welded to the surface of the outer tube 6 so that the tubes with their connecting parts practically constitute an integral inseparable element which can never leak.

A burner 13 is located centrally beneath the lower end of the inner tube 5 and extends upward from an air mixer which consists of a bell-shaped or flaring enlargement 14 depending below the burner and having arms 75 which radiate from a central boss 15, and connect to the lower end of the enlargement. A pipe 16 which is exteriorly screw threaded has its lower end adjustably screwed into a base or pedestal 17 and its upper end adjustably screwed into an opening in a T-coupling 18 which is connected by piping 19 to a source of gas supply. A short pipe 20 has its ends screwed into the boss 15 of the bell shaped enlargement and the T-coupling 18. An air regulating disk 21 is adjustably mounted on the pipe 20 and is adjustable in a vertical direction to regulate the volume of air admitted into the bell-shaped enlargement 14. A nozzle 22 is 85 fitted in the upper end of the pipe 20. A cup 23 arranged around the burner serves to catch the drip caused by condensation. This cup is preferably made integral with the burner.

Within the inner tube 5 which constitutes the fire tube is arranged a series of deflecting elements which serve to muffle the noise of the burner and to deflect the heat against the surface of the tube, causing the flame, 100 the heat and the products of combustion to follow a circuitous path in passing through the tube and thereby more efficiently heating the tube. These elements consists of skeleton elements having radial arms and tubular elements. The lower element has a series of arms 24 preferably four in number which radiate from a common central body 25 and a stem 26 which screws into a central opening in the perforated top portion of the 110 burner. This element is arranged horizontally with the arms extending horizontally.

Above the lower element is located a series of similar elements 27 preferably six in number which are arranged in vertical and horizontal positions as shown in Fig. 1. The 5 arms of those arranged in vertical position extend diagonally and the arms of those arranged in horizontal position extend horizontally and serve to interrupt the flow of the flame and to deflect it into contact with the inner tube. The arms of the vertical 10 elements act as supports for the horizontal elements and also serve to separate the horizontally arranged elements and provide passages for the heated gases and products of combustion. Above the radial arm elements 15 are arranged a series of tubular elements in a vertical row. Each of these elements consists of a tube 28 having a series of slots 29 for the passage of the products of combustion 20 and a flange 30 which extends outwardly from about midway of the tube. The ends of the tubular elements are 25 closed and the slots 29 are cut in the circular side walls of the elements in two circular rows, one being arranged above the flange 30 and the other below the flange so that the products of combustion pass into the tubular element through the lower series of slots and out through the upper series of slots and 30 thus follow a circuitous path and are deflected against the inner tube to rapidly heat the same.

A top 31 is arranged over the upper ends of the tubes and has an overhanging flange 32 and a central upwardly extending tubular portion 33 to which the lower end of a chimney pipe 34 is attached.

The tubular elements are supported by a depending rod 35 which has an eye at its 40 upper end through which a transverse bar 36 passes. This bar is supported in V-shaped depressions in lugs 37 forged on opposite sides of the interior of the upwardly extending tubular portion 33 of the top 31. The rod passes through openings 38 in the tubular elements and a nut 39 screwed upon the lower end of the rod retains the tubular 45 elements in place therein. The top 31 also has a short depending annular flange 40 which fits within the upper end of the fire 50 tube 5 and serves to secure the top in place.

The outlet pipe 41 for hot water is attached to the upper pipe connection 10 and is connected at its other end to the pipe 4, 55 and the inlet pipe 42 for cold water leads from the bottom of the storage tank 1 to the lower pipe connection 11 on the heater see Fig. 1.

A blow off faucet 43 for cleaning purposes 60 is attached to the connection 12 and the gas supply pipe 19 has the usual valve 44.

The operation of the heater will be easily understood from the foregoing description and drawings. The heated gases and the 65 products of combustion first impinge against

the surfaces of the skeleton elements and are separated and deflected in various directions. Upon reaching the tubular elements located in the upper portion of the tube, the gases which have cooled somewhat are collected in the tube and then forced outward in a series of streams against the inner surface of the tube and heating the same. By this means the tube is heated uniformly throughout, as the tubular elements offer more of an obstruction to the passage of the gases than the skeleton elements and enable a large percentage of the remaining heat units of the gases to be convected to the wall of the tube. 80

I claim—

1. In a water heater, two concentric tubes separated sufficiently to leave an annular water space and the inner tube being open throughout to constitute the fire tube, a 85 burner beneath the tubes and skeleton deflecting elements within the inner tube, each having a central body and radial arms extending from said body and located at equal distances apart, one of said deflecting elements being horizontal with its arms extending horizontally, and another being vertical with its arms extending diagonally and serving 90 as supports for the horizontally arranged deflecting element. 95

2. In a water heater, two concentric tubes separated sufficiently to leave an annular water space, a burner beneath the tubes, a series of skeleton deflecting elements within the inner tube having a central body and radial arms, some of said skeleton elements being arranged horizontally with their arms extending horizontally and others being arranged vertically with their arms extending diagonally and serving as supports for 100 the horizontally arranged deflecting elements and tubular deflecting elements within the inner tube above the skeleton deflecting elements. 105

3. In a water heater, two concentric tubes separated sufficiently to leave an annular water space, a burner beneath the tubes and a series of skeleton deflecting elements within the inner tube having a central body and radial arms, some of said skeleton elements being arranged horizontally with their arms extending horizontally and others being arranged vertically with their arms extending diagonally and serving as supports for the 110 horizontally arranged deflecting elements. 115

4. In a water heater, two concentric tubes separated sufficiently to leave an annular water space, a burner beneath the tubes, a series of skeleton deflecting elements within the inner tube having a central body and radial arms, some of said skeleton elements being arranged horizontally with their arms extending horizontally and others being arranged vertically with their arms extending diagonally and serving as supports for the 120 125 horizontally arranged deflecting elements. 130

horizontally arranged deflecting elements and a tubular deflecting element arranged vertically within the inner tube and smaller in circumference than said inner tube, said 5 tubular deflecting element being located above the skeleton deflecting elements and having closed ends and an intermediate annular outer flange which extends in prox-

imity to the inner surface of the wall of the inner tube and being provided with side 10 openings in the walls above and below the flange.

HENRY R. CHURCHILL.
